US0D1030420S

(12) **United States Design Patent** (10) **Patent No.:** **US D1,030,420 S**
(45) **Date of Patent:** **** Jun. 11, 2024**

(54) **HEAT-INSULATING CONTAINER**

(71) Applicant: **ZOJIRUSHI CORPORATION**, Osaka (JP)

(72) Inventor: **Mami Endo**, Nishinomiya (JP)

(73) Assignee: **ZOJIRUSHI CORPORATION**, Osaka (JP)

(**) Term: **15 Years**

(21) Appl. No.: **29/833,426**

(22) Filed: **Apr. 4, 2022**

(30) **Foreign Application Priority Data**

Jan. 25, 2022 (KR) 30-2022-0003401

(51) **LOC (14) Cl.** **07-10**

(52) **U.S. Cl.**

USPC **D7/608; D7/602**

(57) **CLAIM**

The ornamental design for a heat-insulating container, as shown and described.

DESCRIPTION

FIG. 1 is a perspective view of a heat-insulating container showing the claimed design;

FIG. 2 is a front view thereof, a rear view being a mirror image thereof;

FIG. 3 is a left side view thereof, a right side view being a mirror image thereof;

FIG. 4 is a top view thereof; and,

FIG. 5 is a bottom view thereof.

The dashed broken lines in the figures show portions of the heat-insulating container that form no part of the claimed design.

The dot-dash broken lines in the figures show boundaries that form no part of the claimed design.

1 Claim, 4 Drawing Sheets
